SELF-THREADING AND THREAD-TENSIONING SHUTTLE

Arthur G. Russell, Longmeadow, Mass., assignor to Bigelow-Sanford Carpet Co., Inc., Thompsonville, Conn., a corporation of Massachusetts

Application April 17, 1940, Serial No. 330,074

10 Claims. (Cl. 139—217)

This invention relates to an improved automatic self-threading and thread-tensioning shuttle providing an improved shuttle for use with an automatic bobbin changing unit, particularly for carpet looms, which shuttle will both satisfactorily thread itself and supply the necessary high tension for carpet work on the first pick as well as on subsequent picks. Though various self-threading automatic shuttles are on the market, none of these in my experience has proved to be satisfactory in carpet looms because they have not both threaded automatically and operated with the required high tension on the first pick. In such prior devices tension members commonly include a pair of pads held together by a spring but when sufficient tension has been put upon the spring for carpet work such prior devices as tried by me either would not thread automatically on the first pick, or, if the spring were loosened sufficiently so that it did thread automatically, there was insufficient tension on the thread. To overcome such difficulties, my present tension device was devised and has proved satisfactory in practice.

The device in its preferred form will be discussed in connection with the drawing, in which:

Figure 1 is a perspective view of a portion of the shuttle of this invention including a bobbin, part of the wooden structure of the shuttle being broken away to better show the tension device as combined therewith;

Fig. 2 is a perspective view showing certain principal parts of the removable tension device as disassembled;

Fig. 3 is a plan view of the tension device in place in the shuttle with more remote parts of the shuttle broken away, the thread being shown in place;

Fig. 4 is a side elevation of the tension device unit separate from the shuttle and including the parts shown in Fig. 2;

Fig. 5 is a vertical cross section of the shuttle taken through the tension device and showing the thread just as the thread starts to enter and becomes tensioned by the tension device as the first pick starts;

Fig. 6 is a vertical cross sectional view similar to that of Fig. 5 but showing the thread as positioned just after the first pick has started; and

Fig. 7 is a cross sectional view similar to Fig. 6 but showing the thread in the normal running position.

Referring to the drawing, in which like numerals represent like parts, a shuttle having a recessed or chambered body 2, usual eye 4, and

longitudinal thread passage 5, is provided with a recess 6 housing a tension device unit, generally designated 8, which comprises a cage 10 with fixed jaw 12 and movable U-shaped jaw 14 which are held in the cage 10 by means of a pin 16. In the preferred form of the device, as shown, the fixed jaw 12 is dovetailed into the cage 10 as well as being held therein by the pin 16 when the parts are assembled by first placing in the cage the movable jaw 14, then the fixed jaw 12, and entering the pin 16 through the holes 10a, 14a, and 12a, so that the movable jaw 14 is slidably held therein with its top lip overlying and contacting with the adjacent top surface 10b of the cage 10. The movable jaw 14 is normally pressed towards the jaw 12 by a spring 18, the pressure of which may be adjustably regulated by a screw 20 (see Fig. 5) which in turn may be locked as by a set screw 22. The entire assembly 10 of the tension device unit 8 is held in position in the shuttle body 2 by a screw 24 (see Figs. 1 and 3) which also serves to prevent any rotation of the tension device unit in the shuttle.

In Figs. 1 and 3 there is shown the thread T, the latter being led from the bobbin B through the tension device and, on the second pick and thereafter, through the eye 4.

The threading into the tension device takes place on the first pick after the transfer of the fresh bobbin into the shuttle whereby the thread, when led across the top of the tension device, is both easily and surely engaged, as shown in Fig. 5, and is subjected to the desired tension during the first pick by the elongated wedge-like opening between the jaws. These jaws provide a ready immediate engagement of the thread on the first pick, and draw the thread down successively to the position shown in Fig. 6, just after the first pick is started, and then finally to the position shown in Fig. 7, which it occupies in regular operation. The thread quickly reaches this position on the first pick because of the slant of the rearward margin of the thread-engaging portions of the surfaces and of their substantially fixed angular relationship. This slant (see Figs. 1 and 4) is forwardly and downwardly towards the eye of the shuttle. The normal level of the thread, as shown in Fig. 7, is opposite the spring 18.

The jaw 14, while movable to and from the jaw 12, maintains a substantially fixed angular relationship thereto despite the fact that the jaws are wedged further and further apart as the thread progresses from the position shown in Fig. 5 to that of Fig. 7. Such substantially fixed

angular relationship results from the relatively wide spacing of the holes 14a in the spaced opposite legs of the U-shaped jaw 14 notwithstanding ample clearance in the holes 14a which permits the freely slideable movement on the pin 16. Because of the fair curves which facilitate easy, certain, and rapid entrance of the thread into initial thread-engaging relationship, as shown in Fig. 5, a tension is at once automatically applied and, because of the substantially fixed angular relationship of the spring-pressed jaws and shape of the space therebetween, the tension is somewhat increased as the thread moves downward to the position, shown in Fig. 7, against the pressure of the spring 18. Thereafter the tension remains practically constant at its maximum. It is not essential that the opening between the thread-contacting faces of the jaws be wedge-shaped near its lower end, but there the thread-contacting faces may be parallel, provided the faces are maintained in a substantially fixed relation to one another whatever may be the position of the thread between them.

It will be seen from the above that the invention provides in a shuttle the ready and prompt thread entry between the friction surfaces which secures the high thread tension required in carpet looms both during the first pick as well as on subsequent picks in normal operation.

Having described my invention, what I wish to claim and secure by Letters Patent is:

1. An automatic threading and thread-tensioning shuttle including a shuttle body with a bobbin chamber and an eye providing a longitudinal thread passage centrally of the shuttle, a fixed jaw and a relatively movable jaw for tensioning the thread, located between said chamber and said passage providing a wedge-shaped entrance therebetween to initially engage and tension an entering thread and presenting upper faces merging with substantially lower respective normal thread-engaging tensioning portions of said jaws substantially at the level of said passage, said jaws having their rear thread-engaging margins inclined downwardly and forwardly whereby an entering thread initially engaged and tensioned is urged and moves downwardly towards and to said normal thread-engaging tensioning portions towards said passage, guiding means for said movable jaw to maintain said jaws in substantially fixed angular relationship in their relative movement to and from one another, and means yieldingly urging said jaws together in thread-engaging relation.

2. An automatic threading and thread-tensioning shuttle including a shuttle body with a bobbin chamber and an eye providing a longitudinal thread passage centrally of the shuttle, a fixed jaw and a relatively movable jaw for tensioning the thread, located between said chamber and said passage providing a wedge-shaped entrance therebetween to initially engage and tension an entering thread and presenting upper faces merging in a continuous fair curve with substantially lower respective normal thread-engaging tensioning portions of said jaws substantially at the level of said passage, said jaws having their rear thread-engaging margins inclined downwardly and forwardly whereby an entering thread initially engaged and tensioned is urged and moves downwardly towards and to said normal thread-engaging tensioning portions towards said passage, guiding means for said movable jaw to maintain said jaws in substantially fixed angular relationship in their relative movement to and

from one another, and means yieldingly urging said jaws together.

3. An automatic threading and thread-tensioning shuttle including a shuttle body with a bobbin chamber and an eye providing a longitudinal thread passage centrally of the shuttle, relatively movable thread-tensioning jaws including one U-shaped jaw and another jaw arranged between the legs of the U-shaped jaw, both of said jaws being located between said chamber and said passage providing a wedge-shaped entrance therebetween to initially engage and tension an entering thread and presenting upper faces merging in a continuous curve with substantially lower respective normal thread-engaging tensioning portions of said jaws substantially at the level of said passage, said jaws having their rear thread-engaging margins inclined downwardly and forwardly whereby an entering thread initially engaged and tensioned is urged and moves downwardly towards and to said normal thread-engaging tensioning portions towards said passage, means for maintaining said jaws in substantially fixed angular relationship in their relative movement to and from one another, and means yieldingly urging said jaws together.

4. An automatic threading and thread-tensioning shuttle including a shuttle body with a bobbin chamber and an eye providing a longitudinal thread passage centrally of the shuttle, relatively movable thread-tensioning jaws including one U-shaped jaw and another jaw arranged between the legs of the U-shaped jaw, both of said jaws being located between said chamber and said passage providing a wedge-shaped entrance therebetween to initially engage and tension an entering thread and presenting upper faces merging in a continuous curve of increasing radius with substantially lower respective normal thread-engaging tensioning portions of said jaws substantially at the level of said passage, said jaws having their rear thread-engaging margins inclined downwardly and forwardly whereby an entering thread initially engaged and tensioned is urged and moves downwardly towards and to said normal thread-engaging tensioning portions in said passage, means for guiding the said U-shaped jaw for maintaining it in substantially fixed angular relationship in the relative movement of said jaws to and from one another, and means yieldingly urging said jaws together.

5. An automatic threading and thread-tensioning shuttle including a shuttle body with a bobbin chamber and an eye providing a longitudinal thread passage centrally of the shuttle, relatively linearly movable thread-tensioning jaws, including one jaw having laterally spaced axially aligned holes therein, between said chamber and said passage providing a wedge-shaped entrance therebetween to initially engage and tension an entering thread and presenting upper faces merging in a continuous curve of increasing radius with substantially lower respective normal thread-engaging tensioning portions of said jaws substantially at the level of said passage, said jaws having their rear thread-engaging margins inclined downwardly and forwardly whereby an entering thread initially engaged and tensioned is urged and moves downwardly towards and to said normal thread-engaging tensioning portions towards said passage, a fixed pin passing through said spaced holes and on which the jaw having said holes is slideable, said pin maintaining said jaws in fixed angular relationship in the relative linear movement of said jaws to and from one

another, and means yieldingly urging said jaws together.

6. An automatic threading and thread-tensioning shuttle including a shuttle body with a bobbin chamber and an eye providing a longitudinal thread passage centrally of the shuttle, a fixed jaw and a relatively movable jaw for tensioning the thread, located between said chamber and said passage providing a wedge-shaped entrance therebetween to initially engage and tension an entering thread and presenting upper faces merging with substantially lower respective normal thread-engaging tensioning portions of said jaws substantially at the level of said passage, said jaws having their rear thread-engaging margins inclined downwardly and forwardly whereby an entering thread initially engaged and tensioned is urged and moves downwardly towards and to said normal thread-engaging tensioning portions towards said passage, a removable cage in which said jaws are mounted, guiding means for said movable jaw to maintain said jaws in substantially fixed angular relationship in their relative movement to and from one another, and means yieldingly urging said jaws together in thread-engaging relation.

7. A thread-tensioning device for a shuttle comprising a pair of thread-tensioning jaws presenting opposed faces which are disposed in angular relationship relative to each other, one of said jaws being slidable toward and away from the other jaw, a guide to direct said sliding movement, and a bearing extending away from the face of said slidable jaw in the direction of said guide and engaging said guide to minimize rocking movement of the slidable jaw and to preserve said angular relationship during its sliding movement.

8. A thread-tensioning device for a shuttle comprising a pair of thread-tensioning jaws presenting opposed faces which are disposed in angular relationship relative to each other, one of said jaws being slidable toward and away from the other jaw, a guide engaged by said slidable jaw to direct its sliding movement, and a bearing member secured to the slidable jaw and extending in the direction of the guide therefrom to engage said guide at a point spaced from the point of engagement of the guide with the slid-able jaw whereby to minimize rocking movement of the slidable jaw and to preserve said angular relationship during its sliding movement.
